PREPARATION OF SUBSTITUTED QUINONES

William K. T. Gleim, Orland Park, and Alexander Gaydasch, Brookfield, Ill., assignors to Universal Oil Products Company, Chicago, Ill., a corporation of Delaware

No Drawing. Application September 8, 1949,
Serial No. 114,688

12 Claims. (Cl. 260—396)

1

This invention relates to a process for preparing substituted quinones and particularly for preparing mono-substituted para-benzoquinones.

An object of this invention is to prepare a quinone having a hydrocarbon substituent attached to the quinone ring.

Another object of this invention is to produce an alkyl quinone.

A further object of this invention is to produce 2-tert-butylquinone.

A still further object of this invention is to produce 2,5-di-tert-butylquinone.

One specific embodiment of this invention relates to a process for producing a substituted quinone which comprises oxidizing a mono-ether of a substituted hydroquinone.

Another embodiment of this invention relates to a process for producing an alkyl substituted quinone which comprises oxidizing a monoalkyl ether of a substituted hydroquinone having a hydrocarbon substituent combined with the hydroquinone ring.

A further embodiment of this invention relates to a process for producing a tertiary butylquinone which comprises oxidizing a monoalkyl-ether of a tertiary butylhydroquinone.

A still further embodiment of this invention relates to a process for producing 2-tertiary-butylquinone which comprises oxidizing 2-tertiary-butyl-4-methoxyphenol.

An additional embodiment of this invention relates to a process for producing 2,5-di-tert-butylquinone which comprises oxidizing 2,5-di-tert-butyl-4-methoxyphenol.

Heretofore it has been found difficult to produce substituted quinones and especially to produce mono-substituted benzoquinone. We have found unexpectedly that mono-ethers of hydroquinones having a hydrocarbon substituent bound to the hydroquinone ring are oxidized to the corresponding quinones when employing oxidizing agents comprising alkali chlorate and vanadium pentoxide and also nitrous acid and sodium nitrite.

This method is particularly advantageous in the preparation of monoalkylquinones, as it is much easier to monoalkylate 4-methoxyphenol than it is to produce monoalkylhydroquinone from hydroquinone itself.

In carrying out this process, a monoalkylether of hydroquinone such as 4-methoxyphenol, 2-tert - butyl-4-methoxyphenol and 2,5-di-tert-butyl-4-methoxyphenol is placed in a suitable reactor together with dilute sulfuric acid and an oxidizing catalyst such as vanadium pentoxide,

2

and an oxidizing agent such as potassium chlorate, or sodium nitrite is added slowly while the reaction temperature is kept at a temperature of between about -10° to about $+100^{\circ}$ C.

During this oxidation treatment, the reaction mixture is stirred vigorously, for example, by a motor driven stirrer or by other suitable means. When the oxidation is complete, the reaction mixture is cooled, the crude quinone layer is separated and purified either by recrystallization or steam distillation. The crude quinone which is obtained in a yield of from about 50 to about 90% is then recrystallized generally from alcohol to effect further purification.

The nature of the present invention and type of results obtained are indicated by the following examples, although the data presented therein should not be misconstrued to limit unduly the broad scope of the invention.

Example I

Tertiary butylquinone was produced in one run by the following procedure: 90 grams ($\frac{1}{2}$ mole) 2-t-butyl-4-methoxyphenol was suspended in 150 cc. H₂O at 47° , then 10 grams concentrated H₂SO₄ and 0.5 grams V₂O₅ were added with vigorous stirring. A solution of 0.2 mol KClO₃ in 125 cc. H₂O was added slowly in such a way as to keep the temperature at 50° . After all of the chlorate solution was added the reaction mixture was stirred for one hour at 47° . When the reaction mixture has cooled, the crude quinone layer was separated in a separating funnel, and steam distilled while adding about 5 grams CaCO₃. The yield was about 45 grams of crude quinone (55% yield) which when recrystallized from alcohol, yielded yellow needles, of M. P. 59° .

Two grams of this material was hydrogenated at room temperature under 60 lbs. H₂ pressure with 2 grams of Ni hydrogenation catalyst. Crystals of M. P. $126-127^{\circ}$ were obtained. This material did not give depression in a mixed M. P. with authentic 2-t-butyl-hydroquinone of M. P. $125-127^{\circ}$.

Example II

In another run, tertiary butylquinone was prepared as follows: Thirty-three grams 2-t-butyl-4-methoxy-phenol was dissolved in 50 grams methanol, and 10 grams concentrated H₂SO₄ was added. This mixture was stirred vigorously and cooled to $+5^{\circ}$. A solution of 15 grams NaNO₂ in 25 cc. H₂O was added slowly. The temperature was not permitted to exceed 10° . After about one hour, the reaction was

terminated by the addition of 1 gram urea and the whole mixture was steam-distilled. A 20 gram yield of tertiary butyl quinone was obtained, this being equivalent to 66% of the theoretical yield.

Example III

2,5-di-tertiary butylquinone was prepared as follows: Twelve grams, 2,5-di-t-butyl-4-methoxyphenol was dissolved in 100 grams CH₃OH. Seven grams powdered NaNO₂ was added while stirring vigorously. A solution of 6 grams concentrated H₂SO₄ in 25 cc. H₂O was added dropwise. The temperature increased from 20 and 24°. When fumes of NO₂ started to appear, the reaction was terminated by addition of 1 gram of urea. The reaction mixture was filtered from 10.9 grams di-t-butylquinone M. P. 150°. Total reaction time about 1/2 hour, yield 93%.

We claim as our invention:

1. A process for producing a quinone having a hydrocarbon substituent on the quinone ring which comprises oxidizing a monoether of a hydroquinone in the presence of an oxidizing agent selected from the group consisting of alkali chloride, vanadium pentoxide, nitrous acid and sodium nitrite.

2. A process for producing an alkyl quinone which comprises oxidizing a monoalkyl ether of a hydroquinone having a hydrocarbon substituent combined with the hydroquinone ring in the presence of an oxidizing agent selected from the group consisting of alkali chloride, vanadium pentoxide, nitrous acid and sodium nitrite.

3. A process for producing a tertiary butyl-quinone which comprises oxidizing a monoalkyl-ether of a tertiary butylquinone in the presence of an oxidizing agent selected from the group consisting of alkali chloride, vanadium pentoxide, nitrous acid and sodium nitrite.

4. A process for producing 2-tertiary-butyl-quinone which comprises oxidizing 2-tertiary-butyl-4-methoxyphenol in the presence of an oxidizing agent selected from the group consisting of alkali chloride, vanadium pentoxide, nitrous acid and sodium nitrite.

5. A process for producing 2,5-di-tert-butyl-quinone which comprises oxidizing 2,5-di-tert-butyl-4-methoxyphenol in the presence of an oxidizing agent selected from the group consisting of alkali chloride, vanadium pentoxide, nitrous acid and sodium nitrite.

50

6. A process for producing a quinone having a hydrocarbon substituent on the quinone ring which comprises oxidizing a monoether of a hydroquinone at a temperature of from about -10° to about +100° C. in the presence of an oxidizing agent selected from the group consisting of alkali chloride, vanadium pentoxide, nitrous acid and sodium nitrite.

7. A process for producing 2-tertiary-butyl-quinone which comprises oxidizing 2-tertiary-butyl-4-methoxyphenol by treatment with concentrated sulfuric acid and vanadium pentoxide at a temperature of from about -10° to about +100° C.

8. A process for producing 2-tertiary-butyl-quinone which comprises oxidizing 2-tertiary-butyl-4-methoxyphenol by treatment with concentrated sulfuric acid, vanadium pentoxide, and potassium chloride at a temperature of from about -10° to about +100° C.

9. A process for producing 2-tertiary-butyl-quinone which comprises oxidizing 2-tertiary-butyl-4-methoxyphenol by treatment with concentrated sulfuric acid and sodium nitrite at a temperature of from about -10° to about +100° C.

10. A process for producing 2,5-di-tert-butyl-quinone which comprises oxidizing 2,5-di-tert-butyl-4-methoxyphenol by treatment with concentrated sulfuric acid and vanadium pentoxide at a temperature of from about -10° to about +100° C.

11. A process for producing 2,5-di-tert-butyl-quinone which comprises oxidizing 2,5-di-tert-butyl-4-methoxyphenol by treatment with concentrated sulfuric acid, vanadium pentoxide, and potassium chloride at a temperature of from about -10° to about +100° C.

12. A process for producing 2,5-di-tert-butyl-quinone which comprises oxidizing 2,5-di-tert-butyl-4-methoxyphenol by treatment with concentrated sulfuric acid and sodium nitrite at a temperature of from about -10° to about +100° C.
